(57) **CLAIM**

The ornamental design for a conductive seal of a biomedical signal recorder with a radio function, as shown and described.

DESCRIPTION

FIG. 1 is a front view of a conductive seal of a biomedical signal recorder with a radio function, showing our new design;

FIG. 2 is a rear view thereof;

FIG. 3 is a top view thereof, the bottom being symmetrical; FIG. 4 is a right side view thereof, the left side being symmetrical;

FIG. 5 is a cross sectional view thereof, taken along the line 5-5 in FIG. 1; and,

FIG. 6 is a reference view thereof, showing a state of separated components of the sheet.

The broken lines shown in FIG. 5 are for environmental purposes only and form no part of the claimed design.
